UNITED STATES PATENT OFFICE.

JOHN J. MCGILLIS, OF MARINETTE, WISCONSIN.

SAW-MILL DOG.

SPECIFICATION forming part of Letters Patent No. 293,186, dated February 5, 1884.

Application filed October 21, 1882. (No model.)

To all whom it may concern:

Be it known that I, JOHN J. MCGILLIS, a citizen of the United States, residing at Marinette, county of Marinette, and State of Wisconsin, have invented certain new and useful 5 Improvements in Saw-Mill Dogs, which are fully described in the following specification, reference being had to the accompanying drawings, in which—

10 Figure 1 represents a side elevation of one of the side pieces of the carriage, showing the dogs at either end. Fig. 2 is a view of the other side of the same side piece, with a portion of the casing of said side piece removed 15 to show the application of the lever to the dogs. Fig. 3 is a plan view, showing the way in which the dogs are applied to the side piece of the saw-mill carriage. Fig. 4 is a side elevation of the dogs, connecting-rods, and lever 20 by which the dogs are operated. Fig. 5 is an enlarged sectional view taken on the line xx , Fig. 2. Fig. 6 is a transverse sectional view taken on the line yy , Fig. 2. Fig. 7 is an end elevation of a part of the carriage, showing 25 one set of dogs. Fig. 8 is a detached view of one of the link-bars B. Fig. 9 is a detached view of the link which connects the dogs to the link-bar B, and Fig. 10 is a side elevation of one of the dogs.

30 The object of my invention is to enable an operator to dog a log to be sawed by a single lever, which is arranged on the carriage that carries the log in such a manner that the operator by vibrating the lever can apply the dogs 35 to the log for removal, the lever being connected by means of connecting-rods to the dogs at each end of the log in such a manner as to enable their application by a single stroke of the lever. In this manner the log is dogged 40 and undogged readily and without delay, so that no time is lost in performing that work.

45 My invention consists in the combination of the dogs, connecting-rods, and lever in a saw-mill carriage, as hereinafter fully specified and described.

The carriage-frame on which the log to be sawed rests may be constructed in any well-known way adapted to receive the dogs, as hereinafter fully described.

50 The dogs A are made substantially in the

form shown in Fig. 10, and they are arranged at each end of the carriage side by side, each dog lying in a recess or groove, C. I preferably arrange several of these dogs side by side, and connect them with bolts D, which pass 55 through them, so that the dogs are all operated together by means of the connecting-link L, which is attached to the dogs, as shown.

B is a link-bar placed in a recess or groove 60 between guides E.

F is a connecting-rod that connects the link-bar B to the lever G. This connecting-rod F is attached to the link-bar B by hooking it through one of the holes in the link-bar, and by changing it from one hole to another the 65 dogs are adjusted to logs of different lengths.

G is a lever having fulcrum at H, and I is a notched segment adapted to hold the lever at any desired position.

It will be observed that the same system 70 of dogs and connecting-rods is operated at each end of the log from the lever G, and the dogs A are all moved back and forth in their groove C simultaneously; but the connecting-link is so attached to them that the dogs, in 75 entering the ends of the logs, will conform somewhat to the irregular shape of the ends. The dogs in the upper grooves will enter the end of the log, and the dog in the lower groove can still advance sufficiently far to enter the 80 end of the log, if it is not cut evenly, and vice versa. It will be observed that the long grooves in which the dogs are placed allow a long stroke of the lever, so as to adapt the application of the dogs to logs of different lengths, 85 and, as before stated, the connecting-rods can be adjusted to different holes in the link-bar B, so as to allow the application of the dogs to longer or shorter logs when there is a very great variation in their lengths. These hooked 90 dogs A project their sharp ends sufficiently far to enter the log in a manner to hold it firmly in place, and the operator by a single stroke of the lever G can immediately remove and apply the dogs to a log, and the toothed segment I holds the dogs firmly clasped in the end of the log by the means clearly shown in the drawings.

I find by the practical application and use 95 of my saw-mill-dogs that I am enabled to fa- 100

cilitate the labor of dogging logs to be sawed and save a good deal of time and expense. The size of the dogs and their forms and shapes may be varied, and the dimensions of the different parts may be changed to adapt them to carriages of different sizes; and it will be readily seen that the dogs may be applied to the side of the log as it is rolled upon the carriage, or to the bottom of the log, as may be preferred. In my application, however, I have applied them to the side of the log, and find that my system of dogs works very efficiently and readily.

Having thus described the construction and operation of my invention, what I claim as new, and desire to secure by Letters Patent, is—

1. In a saw-mill, an ordinary reciprocating carriage on which the log rests, in combination with one or more dogs arranged at each end of the carriage, and mounted thereon in a way to permit a reciprocating movement of said dogs on the carriage, a lever on the carriage, and devices for connecting the respect-

ive dogs to said lever, whereby the dogs may be operated simultaneously and from one position to dog and undog the logs upon the carriage, substantially as described.

2. In a saw-mill, the log-carriage provided with grooves C at each end, in combination with dogs A, arranged to slide in said grooves at each end of the carriage, the links L, the link-bars B, the connecting- rods F, and the lever G, substantially as and for the purposes set forth.

3. The reciprocating log-carriage, in combination with the sliding dogs A at each end thereof, the lever G on the carriage, the rods F, connecting the dogs at the respective ends of the carriage to the lever on opposite sides of its pivot, the notched segment I, and a pawl on the lever arranged to engage with said segment, substantially as and for the purposes set forth.

JOHN J. McGILLIS.
